CLAIM

The ornamental design for a combination support rack and bowl for barbecue accessories, as shown and described.

DESCRIPTION

FIG. 1 is a perspective view of a combination support rack and bowl for barbecue accessories showing my new design;

FIG. 2 is a side elevational view thereof;

FIG. 3 is a front elevational view thereof;

FIG. 4 is a rear elevational view thereof;

FIG. 5 is a top plan view thereof; and

FIG. 6 is a bottom plan view thereof.

The grill and tool shown in broken lines in FIG. 1 are for illustrative purposes only and form no part of the claimed design.

FIG. 1.

FIG. 2.

FIG. 3.

FIG. 4.

FIG. 5.

FIG. 6.
